UNITED STATES PATENT OFFICE.

GEORGE HOLTZ, OF JERSEY CITY, NEW JERSEY.

FOLDING CARRIAGE.

SPECIFICATION forming part of Letters Patent No. 729,177, dated May 26, 1903.

Application filed October 9, 1902. Serial No. 126,398. (No model.)

To all whom it may concern:

Be it known that I, GEORGE HOLTZ, a citizen of the United States, residing in Jersey City, in the county of Hudson, in the State of New Jersey, have invented a certain new and useful Improvement in Folding Carriages, of which the following is a specification.

The invention is intended more particularly to serve in small sizes for baby-carriages, and I will describe it as thus carried out.

The importance of making a child's carriage foldable or collapsible has been long appreciated. It is particularly important in connection with tall buildings having families living on the upper floors and involves great convenience in carrying a carriage up and down either by the stairs or elevators in a compacted form.

My invention involves improvements in means for contracting the carriage transversely, longitudinally, and vertically.

The following is a description of what I consider the best means of carrying out the invention.

The accompanying drawings form a part of this specification.

Figure 1 is a side elevation, and Fig. 2 an end view. These figures show the construction extended conditioned for use. Fig. 3 is a side elevation of the construction folded. Fig. 4 is an end view corresponding to Fig. 3. Figs. 5, 6, and 7 represent details detached. Fig. 5 is an elevation. Fig. 6 is a plan view with the cross-bar in the act of being closed, with the front of the carriage in its widened condition for use. Fig. 7 shows the same parts after the closure has been completed. Fig. 8 shows a modification. It is a side view of one of the spring-bearings for the axle.

Similar letters of reference indicate corresponding parts in all the figures where they appear.

A and B are the two side frames which form the main skeleton of the construction. Certain portions will be designated when necessary by supernumerals.

A' and B' are the bottom rails of the respective frames, and A² and B² are springs riveted thereto and strongly but yieldingly supporting the carriage upon the wheels W through perforated metal blocks D D, each

of which has an external sleeve D', cast or otherwise formed integral therewith, extending horizontally outward. Each sleeve is 55 smoothly finished and its exterior forms a bearing for one of the main wheels.

D²D² are nuts fitted by screw-threads, each on the end of a sleeve and holding the wheel thereon.

E is a shaft tapped in one sleeve and extending inward. At its inner end the diameter is reduced, as shown at E', and to this is secured by a knuckle E² an extension E³E⁴, a short length E³ being small and the main 65 part E⁴ beyond being of the same diameter as the main part E. When the structure is in the collapsed condition, as shown in Figs. 3 and 4, the entire length of the extension E³E⁴ is outside of the structure, and I turn 70 it upward and cause it to lie parallel to the side of the wheel. It may be fastened in that position by a strap or string. (Not shown.) When the structure is to be extended, one of the preparatory steps is to unfold this axle 75 by extending the portion E³E⁴ horizontally in line with the portion E E'. Then on applying moderate force the two frames A and B are moved apart, the knuckle E² and the extension E³E⁴ being by the extending of the 80 main frame drawn inward and caused to lie within the block D and in the space between the two blocks.

T is a sleeve adapted to slide on the small parts E' E³ of the axle of less length so that 85 it may be moved axially thereon. It has a collar T' at one end.

U is a spring which urges the sleeve into the position to cover and stiffen the knuckle. When the extension E³E⁴ is brought down 90 to straighten the jointed axle, the spring U urges the sleeve into the locking position—to the right in Figs. 2, 4, and 5—and as the structure widens by pulling apart the frames A and B these parts serve collectively as a 95 single and nearly rigid piece. When the structure is collapsed again, the collar T' arrests the sleeve, and as force is applied to complete the collapsing movement the spring U is compressed and the knuckle is freed, so 100 that the extension E³E⁴ is easily raised, and the structure is thereby locked in its narrow form.

C' C' are folding extensions loosely riveted

to the high points at the rear ends of the respective frames A and B and each provided with a lateral projection C², which engages with the respective frame when these extensions are turned upward and backward to their fullest extent. The outer ends of each of these extensions is formed with a ring adapted to receive and form a stiff union with a cross-piece C, of hard wood. (Shown in Fig. 2.) The carriage in the extended condition is operated in the same manner as other carriages, the attendant grasping the cross-piece C.

The front wheels are marked X X. Each runs on a finished lateral arm G², formed integral with the sliding side frames G G'. There are two of these side frames, each having a horizontal portion G, which is toothed, as indicated by g, and is guided in supports in the frames A and B. The front end of each of these side frames is bent sharply downward, as indicated by G'.

H H are two front frames pivoted to the main frames A and B, respectively, and capable of being more than half-revolved thereon. Each is provided with an internally-toothed segment H' h', forged or cast integral with the respective frames H, and the parts are arranged so that the frames H may be raised into the upright position to induce the folded condition of the structure shown in Figs. 3 and 4 and afterward lowered into the horizontal position or still lower into the drooping position. (Shown in Fig. 1.) The latter gives the carriage the character sometimes designated by the term "go - cart." The geared segments H' h', as also the toothed frame G g, are engaged in common with a single small gear-wheel F, on each side loosely carried, by means of pivots A⁵ and B⁵, on short downward extensions from the frames A and B, as shown in Figs. 1 and 2. These gear-wheels F are sufficiently wide to engage with each, and it follows that the raising and lowering of these pivoted front frames H insures that the wheels F shall be turned and that the frames G G', and consequently the front wheels X, shall be correspondingly moved forward and backward. The raising of the front frames H into the upright position turns the wheels F so far that the frames G are slid back to their extreme rearmost position. In this position the back ends of the frames G nearly coincide with the back end of the bases of the side frames A and B. Thus positioning the parts effects the desired contraction of the carriage longitudinally. When the carriage is to be again put in condition for use, the frames H are forcibly turned forward and downward, and the motion acting through the gear-wheels F insures that the front wheels shall move forward into the positions for use shown in Fig. 1.

I I' I² are longitudinal hinged braces loosely riveted each at its rear end to the corresponding frame A or B and loosely riveted at its front end to the frame G' on its respective

side. When the carriage is extended for use, these hinged braces should drop into the straight position. If they do not do so of their own accord, they should be touched by the hand. The joint is a rule-joint, and it is arrested in the proper straight condition. When the carriage is to be folded again, one of the preparatory steps is to deflect these braces upward at the mid-length by touching with the fingers or otherwise.

The main frames A and B are strongly but extensibly connected by hinged cross-braces J J' J², of which J and J² are of equal lengths, 8c united by a rule-joint J', and loosely riveted at their ends to the frames A and B, respectively. This brace is depressed into the horizontal position to maintain the proper distance apart of the frames when the carriage is extended. To collapse the carriage, this brace must be deflected upward at the center. The front of the structure is transversely braced and released in a different manner.

K is a bar of steel or other suitable material loosely riveted to a short arm extending around from the front and lower end of one of the frames G G' on the inside and arranged to swing horizontally. When the carriage is in the collapsed condition, this bar extends 95 longitudinally and idly along the interior of the structure. When the carriage is extended for use, this bar K is swung around into a position transverse of the structure and the previously-free end properly formed for engagement, as shown, is united to a short arm G² conversely formed, extending inward from the opposite frame G' and carrying a longitudinally-sliding sleeve L, loosely secured by a screw K', received in a slot l. The short arm 100 G² carries a horizontal pin G³ and the bar K is equipped with a hole k to receive it. The meeting surfaces are beveled and rounded, as shown, and on swinging the bar K into position it presses the sleeve out of the way and 105 snaps into place, and the sleeve, urged inward by a spring M, engages it. The bar K thus engaged serves as an efficient distance-piece, holding the front of the structure firmly to the proper width. When the carriage is to 110 be collapsed, the sleeve L is pressed outward by the fingers against the gentle force of the spring M and the bar K is swung a quarter-revolution on its pivot and is idle again, after which the front of the structure is free to be 115 contracted laterally.

The upper rails A⁶ B⁶ of the respective side frames A B serve both as a hand-rail for the child and as a convenient handle for transporting the collapsed carriage.

A⁸ is a short spring, which may be of similar steel to the longer spring A², but preferably thinner. It contributes to the support, especially against lateral strains.

P is a long slotted support pivoted to the 130 front H and taking hold by its slot p of a pin A⁴. There is one on each side. They contribute to hold the front frame H against its descent too low under any conditions when

extended, and by means of a notch p' in the side of the slot p , engaging with the pin A^4 , they hold the structure reliably in the folded condition.

5 Modifications may be made without departing from the principle or sacrificing the advantages of the invention.

I have in my experiments made the frames A and B and most of the parts of cast metal; 10 but this may be varied, taking care to have them as light as practicable. The curves and contours of the several parts may be varied to promote a pleasing effect on the eye or for other purposes. Lattice-work or fabric of various grades may be used to complete the body. The bottom may be thin wood in two 15 portions, hinged together and to the side frames A and B, as will be obvious.

Fig. 8 shows provisions by a rigid jaw carried on the side frame for supporting the spring-bearing laterally, which connects the main body to the main shaft E.

I claim as my invention—

1. In a collapsible carriage the main axle 25 arranged to slide through one of the wheel-centers and having portions of a reduced diameter and a knuckle-joint in such reduced portion, in combination with the sleeve T adapted to be shifted longitudinally of the 30 shaft for stiffening the latter, all arranged for joint operation substantially as herein specified.

2. In a collapsible carriage the main axle arranged to slide through one of the wheel- 35 centers and having portions of a reduced diameter and a knuckle-joint in such reduced portion, in combination with the sleeve T adapted to be shifted longitudinally of the shaft for stiffening the latter, and the spring 40 U for automatically operating it to maintain the extended condition of the carriage, all arranged for joint operation substantially as herein specified.

3. In a collapsible carriage the main axle 45 arranged to slide through one of the wheel-centers and having portions of a reduced diameter, and a knuckle-joint in such reduced portion, in combination with the sleeve T adapted to be shifted longitudinally of the 50 shaft, arranged to present such joint close to the exterior of the wheel when the carriage is contracted so that the part $E^3 E^4$ serves the double function of prolonging the axle at one period and of locking the parts in the contracted condition at another period, all substantially as herein specified.

4. In a collapsible carriage-wheel bearings constructed as sleeves on blocks carrying the weight through the medium of springs, the

main axle arranged to slide through one of the wheel-centers and having a knuckle to allow of folding to contract the width of the rear end, the combination therewith of the pivoted bar K at the front and lateral engaging arm G^2 and the pin G^3 engaging in the 60 hole k adapted to hold the extended width of the structure reliably, all arranged to serve substantially as herein specified.

5. In a collapsible carriage, wheel-bearings constructed as sleeves on blocks carrying the 70 weight through the medium of springs, the main axle arranged to slide through one of the wheel-centers and having a knuckle to allow of folding to contract the width of the rear end, the combination therewith of the 75 pivoted bar K at the front and lateral engaging arm G^2 and the pin G^3 engaging in the hole k adapted to hold the external width of the structure reliably, and the sleeve T and spring U to automatically engage the bar 80 when properly placed, all arranged to serve substantially as herein specified.

6. In a collapsible carriage the frames G G' sliding in supports in the main frame A B and carrying the front wheels X with capacity to move apart and together laterally, and also to expand and contract in the length, the hinged frames H each having geared segments H' , independent on the two sides and the gear-wheels F engaging with teeth both 90 on the frames G and segments H' , all combined and arranged to serve substantially as herein specified.

7. In a collapsible carriage the main axle arranged to slide through one of the wheel- 95 centers and having portions of a reduced diameter and a knuckle-joint in such reduced portion, in combination with the sleeve T adapted to be shifted longitudinally of the shaft, arranged to present such joint close to 100 the exterior of the wheel when the carriage is contracted so that the part $E^3 E^4$ serves the double function of prolonging the axle at one period and of locking the parts in the contracted condition at another period, the frames 105 A B having horizontal top bars $A^6 B^6$ adapted to serve both as hand-rails for the child and as handles for easy transportation of the collapsed carriage, all substantially as herein specified.

In testimony that I claim the invention above set forth I affix my signature in presence of two witnesses.

GEORGE HOLTZ.
